AMBROSE H. WHITE, OF BROOKLYN, NEW YORK.

DRYING-CYLINDER.

1,189,761.

Specification of Letters Patent.

Patented July 4, 1916.

Application filed October 22, 1914. Serial No. 867,938.

To all whom it may concern:

Be it known that I, AMBROSE H. WHITE, a citizen of the United States, residing in the borough of Brooklyn, county of Kings, State of New York, have invented certain new and useful Improvements in Drying Cylinders; and I do hereby declare the following to be a full, clear, and exact description of the invention, such as will enable others skilled in the art to which it appertains to make and use the same.

This invention relates to the means employed for heating the peripheral surface of a drying cylinder. It is of special utility in drying cylinders of the type employed in paper-making machinery but it may also be employed in machines for other uses such, for instance, as the manufacture of textile material.

In drying cylinders for paper-making machines as heretofore constructed, it has been common to provide means for supplying live steam to the interior of the cylinder so as to heat the cylinder wall, from which the heat is rather rapidly drawn off by contact with the material to be dried. This contact commonly extends over a large part, but not all, of the outer surface of the cylinder. The admitted steam condenses within the cylinder and the water of condensation, usually contaminated with some amount of lubricating oil, has a substantial insulating effect upon the portion of the cylinder wall with which it is in contact. The degree of this insulating effect depends upon the extent to which the liquid is distributed over the inner wall of the cylinder by the centrifugal force due to rotation of the cylinder, and this in turn depends upon the speed of rotation and the amount of water in the cylinder. In any case the distribution will not be entirely uniform and corresponding variations of the temperature of the cylinder wall will occur. It is common practice to provide means for continuously withdrawing the water of condensation from within the cylinder; but at best this only mitigates the evil, and in practical operation it is found that even when these devices are used the quantity of water within the cylinder will show substantial variations from time to time. Much difficulty has consequently been experienced in maintaining the surface of the cylinder at the relatively high and substantially uniform temperature which is desirable. I

have found that the difficulty may be overcome to such an extent as largely to improve the operation of such cylinders, by introducing the live steam with uniform lengthwise distribution and directly into the water of condensation so as to maintain the temperature of the whole of this water as near the boiling point as possible and make use of it as the immediate agency for distributing the heat of the steam uniformly to the entire wall of the cylinder. I find that this result may be accomplished by introducing the steam into the water of condensation through any suitable conduit which extends lengthwise of the cylinder and discharges the steam beneath, or in a jet or jets against, the water.

In the following disclosure I have made specific reference to preferred embodiments of the invention in which the steam is directed into or against the water from a conduit extending lengthwise of the cylinder and having a plurality of jet orifices directed toward the cylinder wall, but it is to be understood that this preferred form is not essential to the invention, which in its broad aspect includes any suitable means for introducing the steam with uniform lengthwise distribution and directly into the water of condensation within the cylinder.

In the accompanying drawings, Figure 1 is a central longitudinal section of a drying cylinder provided with heating devices constructed in accordance with the invention, and Fig. 2 is a transverse section of a modified form of the invention.

Referring first to Fig. 1, a drying cylinder is shown of the type commonly employed in paper-making machines. This consists of a hollow cylindrical shell 10 and end members 11 and 12 secured to opposite ends thereof. Each of these end members 11 and 12 has a trunnion 13 adapted to be received in suitable bearings. One of the trunnions 13 has an axial opening therethrough for the reception of a steam conduit 14. The inner end of this conduit is connected to a pipe 15, which extends radially outward to a point adjacent to the periphery of the cylinder where it is connected to a steam discharge pipe 16, extending lengthwise of the cylinder close to its interior surface. On the side of the pipe 16 adjacent to the wall of the cylinder, outlets are provided for discharging the steam beneath or against the water of condensation.

so that the steam will be introduced directly into the water. These outlets are preferably in the form of a multiplicity of small openings arranged in line lengthwise of the pipe 16, though other form of opening may be provided for this purpose.

Preferably, but not necessarily, the usual means are provided for the withdrawal of the water of condensation and other liquid 10 collecting within the cylinder. In the present instance, I have shown outlet pipes in the form of a siphon for this purpose. An outlet pipe 17 extends concentrically through the conduit 14 and the fitting 18 15 connecting the conduit 14 with the pipe 15. Within the cylinder the outlet pipe 17 has a branch pipe 19 secured thereon and extending radially outward to a point adjacent to the peripheral wall of the cylinder. The opposite end of the outlet pipe 17 passes 20 through the wall of a fitting 20 and is connected with a discharge pipe 21. The fitting 20 is provided for the purpose of connecting the conduit 14 with a steam supply pipe 22. 25 The order to reinforce the parts lying within the hollow cylinder, I prefer to extend the outlet pipe 17 throughout the length of the cylinder and to locate its end in a concentric opening in the trunnion upon the end member of the cylinder opposite 30 that through which the conduit 14 passes. Also the end of the steam discharge pipe 16 opposite that which is connected to the pipe 15 may be joined to the pipe 17. Such a connection is shown at 23, a piece of piping being employed for this purpose though this piping is not in communication with the outlet pipe 17.

In the operation of a machine employing 40 this form of drying cylinder, steam would be admitted through the pipe 22, conduit 14 and pipe 15, to the steam discharge pipe 16, and from this pipe the steam would pass out through the numerous openings provided therein toward the adjacent wall of the cylinder, and into the water of condensation. In any case, the heat of the steam forcibly introduced into the water of condensation will be rapidly disseminated 45 throughout the water, by conduction and convection and by the circulation of the water incident to the rotation of the cylinder, and the temperature of the water uniformly maintained close to the boiling point. 50 In this way the relatively high and substantially uniform temperature of the cylinder wall which is found to be so necessary to proper operation of a paper-making machine, may be readily maintained and the detrimental effects resulting from uneven heating of the surface of the drying cylinder are avoided.

The arrangement particularly described provides a substantially uniform distribution of the injected steam lengthwise of the

cylinder, and has the additional advantage that the line of steam jets extended lengthwise of the cylinder form a barrier which tends to bank up the water of condensation into a pool from which the water is withdrawn through the siphon 19.

Although I have shown in Fig. 1 a single steam-discharge pipe within the cylinder and located at the lower portion thereof, it will be understood that the pipe may be located at any other portion of the cylinder and that a number of pipes may be employed if desired, as indicated in Fig. 2 in which three pipes 16 are arranged at equal distances apart around the cylinder, the arrangement being otherwise the same as that of Fig. 1.

In order that the heating effect of the steam shall be applied with uniformity to the drying cylinder, it is desirable that the steam pipe or pipes and the drying cylinder shall be relatively rotatable with respect to each other. Thus, in the constructions illustrated, the steam pipe or pipes are stationary, so that the cylinder is relatively rotatable with respect thereto.

So far as I am aware, it is broadly new to introduce the steam, in such a drying cylinder, into the water of condensation to maintain that water at a uniformly high 95 temperature and make use of it as the agency for distributing the heat of the steam to the cylinder wall, and the appended claims should have a correspondingly broad interpretation.

What I claim is:

1. A steam-heated drying cylinder in which water of condensation collects, said cylinder having means for introducing heating steam with uniform lengthwise distribution directly into the water of condensation, whereby the water is maintained at a uniform high temperature and serves as the agency for distributing the heat of the steam to the cylinder wall.

2. A steam-heated drying cylinder in which water of condensation collects, said cylinder having means for introducing heating steam with uniform lengthwise distribution directly into the water of condensation, whereby the water is maintained at a uniform high temperature and serves as the agency for distributing the heat of the steam to the cylinder wall, and means for withdrawing from the cylinder the excess water 120 of condensation.

3. A steam-heated drying cylinder having a steam conduit located within the cylinder and extending longitudinally thereof adjacent to the peripheral wall thereof and provided with outlets for directing steam issuing therefrom toward the peripheral wall of the cylinder and means for conveying steam from the exterior of the cylinder to said conduit.

4. A steam-heated drying cylinder having trunnions at its ends, supports passing through the trunnions, and a steam conveying and distributing pipe within the cylinder mounted on said supports and extending lengthwise of the cylinder close to the peripheral wall thereof, said pipe having outlet openings on the side thereof toward the adjacent wall of the cylinder.
5. A steam-heated drying cylinder having a conduit for carrying steam to the interior thereof, a pipe connected to said conduit and located within the hollow cylinder extending lengthwise thereof close to the interior surface of the peripheral wall of the cylinder and provided with outlets for delivering steam toward said surface with substantially uniform lengthwise distribution, and means for withdrawing water of condensation from the interior of the cylinder.
6. A steam heated drying cylinder in which water of condensation collects and from which said water must be withdrawn, said cylinder having means for introducing heating steam directly into the water of condensation whereby the water is maintained at a uniform high temperature and serves as the agency for distributing the heat of the steam to the cylinder wall, said
- 10 cylinder and steam introduction means being relatively rotatable with respect to each other.
7. A steam heated drying cylinder having trunnions at its ends, supports passing through the trunnions, and a steam conveying and distributing pipe within the cylinder mounted on said supports and extending lengthwise of the cylinder close to the peripheral wall thereof, said cylinder and pipe being relatively movable with respect to each other and said pipe having outlets in the side thereof adjacent to the wall of the cylinder and through which heating steam is discharged toward said wall; substantially as described.
8. A revoluble drying drum, hollow trunnion therefor, said drum having a plurality of perforated conduits extending parallel with the axis thereof and located therein adjacent to the inner periphery thereof; and means for supplying said conduits with heated vapor admitted through a trunnion of said drum.
9. In testimony whereof I affix my signature, in presence of two witnesses.
